(57) CLAIM

The ornamental design for a support bracket for a window sill planter, as shown and described.

DESCRIPTION

FIG. 1 is a perspective view of a support bracket for a window sill planter;

FIG. 2 is a front view thereof;

FIG. 3 is a rear view thereof;

FIG. 4 is a left-hand side view thereof, wherein a right-hand side view is a mirror image of the left-hand side view;

FIG. 5 is a top view thereof; and,

FIG. 6 is a bottom view thereof.
